INVENTOR

Henry Taylor Bottomley

UNITED STATES PATENT OFFICE.

HENRY NAYLOR BOTTOMLEY, OF SHELF, NEAR HALIFAX, ENGLAND.

PATTERN-CHAIN.

SPECIFICATION forming part of Letters Patent No. 735,202, dated August 4, 1903.

Application filed March 3, 1903. Serial No. 145,874. (No model.)

To all whom it may concern:

Be it known that I, HENRY NAYLOR BOTTOMLEY, a subject of the King of Great Britain, residing at Shelf, near Halifax, in the county of York, England, (whose postal address is Clough Mills, Shelf, near Halifax, aforesaid,) have invented certain new and useful Improvements in and Relating to the Pattern - Chain Mechanism of Looms for Weaving, of which the following is a specification.

The object of my invention is to construct the links of pattern-chains employed in what is known as the "Doberross" loom (but which can also be adapted to other kinds of looms) so that the time occupied in changing the pattern is reduced to a minimum. Hitherto in some instances the pattern-links have been formed of a spindle upon which are mounted a number of rings or hoops suitable distances apart, according to the shafts required to be raised in forming the pattern. These hoops are kept in their proper positions by a further number of hoops of a less diameter, and in changing the pattern these hoops and rings take up a lot of time in removing, adding, or adjusting the same for a fresh pattern.

In the accompanying drawings similar letters refer to similar parts throughout the several views.

Figure 1 is a plan view of part of my improved link for forming the pattern-chain employed in looms for weaving. Fig. 2 is a plan view of the retaining-bar of my improved link. Fig. 3 is a plan view of a section of the pattern-chain, showing my improved links or mechanism for operating the shafts of the dobby. Fig. 4 is a side view of Fig. 3. Fig. 5 is a side view of the notched disk used in connection with my improved pattern-chain mechanism. Fig. 6 is a sectional end view of my improved link and means for operating the shafts of the dobby as shown at Fig. 3.

I construct my improved pattern-link in the form of a notched bar A, the number of notches B corresponding with the number of shafts in the dobby, and in place of the hoops or rings hitherto employed for lifting the shafts I employ disks C, having notches D

corresponding in size and shape with the notches in the bar A. These notches D are formed upon diametrically opposite sides of said disks. When these disks C are in position on the notched bar A, the neck E of the disk, formed by the notches in the same, fits within the notch B of the bar. A second or retaining bar F the same length as the notched bar A fits against the notched side of the same within the outer notches in the disks and so holds such disks firmly in the required positions.

A perforation is provided at each end of both bars A and F, through which passes a split pin or spring-cotter G and holds the said bars rigidly together. 65

The notched bar is provided at each end with a suitable neck H to fit the cylinder and with suitable wings J for attachment to the pattern-chain K.

By this construction of pattern links or chain it is not necessary to remove the same when requiring to change the pattern. All that is required is to detach the second bar F by withdrawing the coppers G, when the disks can be easily and quickly removed or adjusted, as desired. Upon replacing the bar F and coppers the pattern is again set, so effecting a great saving in time and labor in this kind of work. My invention in addition to operating the shafts of dobbies may be also employed for lifting or changing the shuttle-boxes in drop-box looms. 80

What I claim as the invention, and desire to secure by Letters Patent, is—

In a pattern-chain, the combination, with a notched bar provided with necks and wings at its ends, of a series of disks having notches at opposite sides, the notches on one side being placed in engagement with the notches of the said notched bar, a locking-bar which engages with the other notches of the said disks, and means for securing the said locking-bar to the said notched bar. 90

HENRY NAYLOR BOTTOMLEY.
